UNITED STATES PATENT OFFICE.

GUSTAVE O. DEGENER, OF NEW YORK, N. Y., ASSIGNEE TO UNDERWOOD COMPUTING MACHINE COMPANY, OF NEW YORK, N. Y., A CORPORATION OF NEW YORK.

KEY-ARRESTING MECHANISM.

1,910,349.

Specification of Letters Patent. Patented Nov. 28, 1911.

Application filed July 29, 1911. Serial No. 641,273.

To all whom it may concern:

Be it known that I, GUSTAVE O. DEGENER, a citizen of the United States, residing in New York city, in the county of New York and State of New York, have invented certain new and useful Improvements in Key-Arresting Mechanism, of which the following is a specification.

This invention relates to a type key locking device for the purpose of preventing more than one key being actuated at a time.

The object of this invention is to provide means whereby, when a single key is struck, an obstruction may be so positioned, that it will prevent the operation of the other keys at the same time. Said obstruction may be in the form of a blade, operatively connected to each of the keys, and adapted to be so actuated, as to prevent the movement of all 20 of the other blades when the key corresponding to any one of the blades has been actuated.

A further object of this invention is to provide, in a typewriter, adding machine, 25 or the like, means whereby only one character key can be actuated at a time, said means being operatively disconnectible so that it can be used or not according to the exigencies of the moment, to control the action of the keys.

These and other objects, together with the construction and combination of the parts, will be more fully described herein-after, and particularly set forth in the 35 claims.

Reference may be had to the accompanying drawings, in which like reference characters denote corresponding parts in the several views, and in which—
40 Figure 1 is a fragmentary section on the line from front to rear of the machine. Fig. 2 is a fragmentary top plan view with parts broken away. Fig. 3 is a fragmentary end view in elevation, looking from right to left in Fig. 2. Fig. 4 is a fragmentary perspective view, showing the connection of one of the key levers to the other mechanism. Fig. 5 is an enlarged horizontal sectional view, showing the action of the obstruction members. Fig. 6 is a fragmentary view in front elevation, partly in section, showing the connection of the key levers to the other mechanism.

Referring more particularly to the separate parts of this invention, as embodied

in the form shown in the drawings, 1 indicates a key lever which actuates through the intermediary of a sub-lever 2, a type-bar 3 in the usual manner.

In view of the fact that the connection 60 with each key lever is the same, only one will be described.

Secured to the key lever 1 in any suitable manner, there is provided a pair of jaws 4 and 5 spaced apart a sufficient distance to 65 permit a hook portion 6 on a link 7 to pass in between them. It will be seen that the hook 6 may slip out at the side from between the jaws, and that the lower jaw projects beyond the upper jaw a sufficient distance to prevent the hook 6 of the link 7 from coming below the opening between the two jaws at any time. The link 7 is pivotally connected at its upper end to a bell crank lever 8, which is pivoted at 9 in any 70 suitable manner, and has connected thereto in any suitable manner, an elongated link 10. The opposite end of the elongated link 10 is pivotally connected to a bell crank lever 11, which is pivotally mounted on a support 12. As stated above, there is one of these mechanisms for each of the keys, and the bell crank levers 11 of the mechanisms are radially disposed on a support 12 in juxtaposition to each other. 75

The bell crank levers 11 are provided at one end with obstructing members 13, which are shown in the form of arcuate blades adapted to play in radial slots 14 provided in a stationary supporting member 15. These 80 blades may be in the form of segments curved about the pivots of their respective levers as centers. The slots 14 all let into a central opening 16, so that any one of the blades can play or move across the same. 85 It will be seen, however, when one of the obstructing members or blades 13 is extended across the opening 16, that it obstructs the movement of all of the other obstructing members or blades 13, so as to prevent them 90 from passing any great distance into the opening 16. It will thus be readily seen, when one of the key levers is depressed to actuate the type bar and any other mechanism which may be connected to it, that one 95 of the obstructing members 13 will be swung across the opening 16, so as to prevent any of the other obstructing members or blades from passing far beyond the inner margin 100 of the slots 14. It will thus be evident that 105 110

when one key has been depressed, the movement of all the other keys will be prevented by the obstruction of the movement of the mechanism connected thereto.

5. It may be often desirable, according to the exigencies of the moment, not to use the locking or interfering mechanism. In such an event advantage can be taken of the fact that the hooks 6 of the links 7 are operatively disconnectible from the jaws 4 and 5 by slipping out through the opening at one side. The links 7 can be manipulated in any suitable manner for this purpose, as for example, by a shifter or rod 17 which is shown 10 as operatively connected thereto by being provided with slots 18 through which the links extend. The rod or shifter 17 may be operated in any manner suitable to the requirements, either manually or automatically. 15

While I have shown one embodiment of my invention, I do not wish to be limited by the specific details thereof, but desire to be protected in various changes, alterations and 20 modifications which may come within the scope of the appended claims.

Having thus described my invention, I claim:

1. The combination with a set of keys, of 30 a set of blades connected thereto, said blades movable by their keys to a position common to all the blades, so that when one blade occupies such common position the other blades and their keys are prevented from operating.

35. 2. The combination with a set of keys, of a set of blades connected thereto, said blades movable by their keys to a position common to all the blades, so that when one blade occupies such common position the other blades 40 and their keys are prevented from operating, and supports for said blades in proximity to said common position.

3. The combination with a set of keys, of 45 a set of supported blades diverging from a common center and connected to said keys to be moved thereby to said common center, so that any blade, upon moving to said common center, may prevent the operation of any of the remaining blades and keys.

50. 4. The combination with a set of keys, of a supporting device having a central opening and slots radiating from said opening, and blades supported in said slots and connected to said keys to be moved thereby into 55 said opening, to enable each blade to prevent the operation of the remaining blades and their keys.

5. The combination with a set of keys, of 60 a set of diverging levers connected thereto, and a set of diverging blades provided upon said levers and movable by said keys to a common position to enable each blade to intercept the remaining blades.

6. The combination with a set of keys, of 65 a set of diverging levers connected thereto,

and a set of diverging blades provided upon said levers and movable by said keys to a common position to enable each blade to intercept the remaining blades, and a support having radial slots in which said blades are guided. 70

7. The combination with a set of keys, of a set of diverging levers connected thereto, and a set of diverging blades provided upon said levers and movable by said keys to a common position to enable each blade to intercept the remaining blades, and a support having radial slots in which said blades are guided, the blades being in the form of segments curved about the pivots of their respective levers. 75

8. The combination with a set of keys, of a set of diverging levers connected thereto, and a set of diverging blades provided upon said levers and movable by said keys to a common position to enable each blade to intercept the remaining blades, the connection between said levers and said keys being such that the one can be detached from the other, so that said keys may operate freely independent of said levers. 80

9. The combination with a set of keys, of a set of movable obstructing members operatively connected to said keys, one of each of the latter corresponding to one of each of the former, said members moving individually to a position in the path of movement of the rest of said members, so as to prevent the simultaneous complete actuation of two or more members and thereby prevent the simultaneous actuation of two or more keys. 85

10. The combination with a set of keys, of a set of movable obstructing members operatively connected to said keys, one of each of the latter corresponding to one of each of the former, said members moving individually to a position in the path of movement of the rest of said members, so as to prevent the simultaneous complete actuation of two or more members and thereby prevent the simultaneous actuation of two or more keys, and guiding means for constraining the movement of said members along predetermined paths. 100

11. The combination with a plurality of 115 keys, of locking mechanism for said keys, said locking mechanism being operatively disconnectible from said keys, so as to permit said keys to move free and independent of said locking mechanism.

12. The combination with a plurality of keys, of locking mechanism for said keys, said locking mechanism being operatively disconnectible from said keys, so as to permit said keys to move free and independent 125 of said locking mechanism, and a shifter for controlling the connection of said locking mechanism with said keys.

13. The combination with a plurality of keys, of a member coöperating with each 130

of said keys to lock certain of the others of said keys, by interfering with the action of said members corresponding to said keys.

14. The combination with a plurality of 5 keys, of a member coöperating with each of said keys to lock certain of the others of said keys, by interfering with the action of said members corresponding to said keys; each of said members being operatively dis- 10 connectible from said keys so as to permit such keys as are disconnected to move inde- pently of the locking or interfering ac- tion of said members.

15. The combination with a plurality of 15 keys, of a member coöperating with each of said keys to lock certain of the others of said keys, by interfering with the action of said members corresponding to said keys; each of said members being operatively dis- 20 connectible from said keys so as to permit such keys as are disconnected to move inde- pently of the locking or interfering ac- tion of said members, and a shifter for con- trolling the operative connection of a plu- 25 rality of said members with said keys simul- taneously.

16. The combination with a key, of a pair 30 of jaws connected to said key and spaced apart from each other, a link adapted to extend in a space between said jaws so as to be operatively connected to said key, and an interfering or locking mechanism connected to said link.

17. The combination with a key, of a pair 35 of jaws connected to said key and spaced apart from each other, a link adapted to extend in a space between said jaws so as to be operatively connected to said key, and an interfering or locking mechanism con- 40 nected to said link, the space between said jaws being open at one side so that said link can move into and out of the space between said jaws so as to operatively connect and disconnect said link with said key, one of 45 said jaws projecting beyond the other of

said jaws at the open side of said space, so as to prevent the jaw-engaging end of said link from passing out of alinement with the open side of said space.

18. The combination with a key, of a link 50 detachably connected to said key, an inter- fering or locking member connected to said link, and a bar having a slot therein through which said link extends for shifting said link to connect and disconnect the same with 55 said key.

19. The combination with a plurality of 60 keys each having a pair of jaws separated to form a space open at the same side, of a plurality of links having hook-shaped 65 portions movable into and out of the space between said jaws through said open sides, locking or interfering mechanism connected to said links so as to be controlled by, and likewise control the action of said keys, and 70 a shifter for manipulating said links, so as to operatively connect and disconnect the same with said keys by moving them into and out of the space between said jaws.

20. The combination with a plurality of 75 keys each having a pair of jaws separated to form a space open at the same side, of a plurality of links having hook-shaped por- 80 tions movable into and out of the space be- tween said jaws through said open sides, locking or interfering mechanism connected to said links so as to be controlled by, and likewise control the action of said keys, and a shifter for manipulating said links, so as to operatively connect and disconnect the 85 same with said keys by moving them into and out of the space between said jaws, one of said jaws having means for preventing the disalinement of the hook-shaped por- tions of said links with said spaces between said jaws.
